UNITED STATES PATENT OFFICE.

KIRK K. WRIGHT, OF KENMORE, NEW YORK.

WASHER.

Application filed February 4, 1928. Serial No. 251,913.

This invention relates to washers for bottles, cans and other like articles.

An object of the invention is to generally improve and simplify washers of this type.

Another object of the invention is to provide an improved washer of this type, with which a single operator may insert and remove the objects or articles to be washed without moving materially from one position; which may be utilized for washing articles of different sizes; with which the articles may be propelled through the washer in a simple manner and under the control of the operator standing between the inlet and outlet openings; and which will be relatively simple and inexpensive.

Various other objects and advantages will be apparent from the following description 20 of an embodiment of the invention, and the novel features will be particularly pointed out hereinafter in connection with the appended claims.

In the accompanying drawings:

25 Fig. 1 is a perspective of a washer constructed in accordance with this invention, and

Fig. 2 is a sectional plan of the same.

In the illustrated embodiment of the invention, the washer may include an elongated tank or vat 1 which may be supported above the floor by suitable posts or legs 2. An enclosure 3 is superimposed over the upper, open face of the tank or vat 1 at 30 one end of the same so as to extend along the tank or vat to within a short distance of the other end and leave an open tank portion 4 in which the cans or articles to be washed may be given a preliminary drain 35 or rinse, if desired. The tank 1 is preferably divided into separate compartments along the same and beneath the enclosure for a purpose which will appear presently.

The enclosure 3 forms a tunnel from end 45 to end and is provided with lateral openings 5 and 6 at the same side of the tunnel. These openings 5 and 6 are spaced apart a short distance so as to be accessible to an operator standing beside the enclosure and 50 between said openings. The opening 5 at the end adjacent the open vat section 4 may be utilized as the inlet opening, and the other opening 6 utilized as the outlet opening.

55 The bottom of the enclosure 3 opens into the vat or tank 1 but is provided with

guides 7 extending from the inlet opening 6 into the tunnel of the enclosure, thence lengthwise along the tunnel, and thence laterally and outwardly through the outlet opening 6. When the articles to be washed are milk bottles, such bottles will be supported in an inverted position in crates or frames 8 having open bottoms, and the crates 8 will be guided through the tunnel 60 upon the guides 7. The openings 5 and 6 are of a size to permit the passage therethrough of such crates or frames 8. Each frame 8 containing the bottles to be washed will be placed upon the guides 7 at the opening 5 and shifted laterally of the enclosure 65 into the tunnel. The crates, after being moved along the tunnel, will be withdrawn through the opening 6 and then carted 70 away.

In the compartments of the tank or vat 1 which are beneath the enclosure 3, various suitable devices for effecting the washing will be arranged so as to operate upon the inverted bottles during their passage 80 through the tunnel of the enclosure. For example, when the articles or bottles are first pushed through the inlet opening 5 into the tunnel, the inverted bottles will be subjected to a suitable cleansing spray, such as of a caustic solution, from nozzles *a*, and thereafter that crate with its bottles will be shifted along the tunnel to a second position in which they will be permitted to drain. When shifted to a further position 90 along the tunnel, they will be subjected to a rinsing spray from nozzles *b* to rinse off the cleansing or caustic solution, and when shifted into the last end of the tunnel adjacent the opening 6, the articles will be 95 given a sterilizing treatment, such as by subjecting them to the action of live steam or steam and water from nozzles *c*. The clean and sterile articles are then withdrawn through the opening 6 and conveyed away 100 for use.

The nozzles *a*, *b*, and *c* may be supplied with the various fluids in any suitable or usual manner, such as through pipes *a'*, *b'* and *c'* controlled by valves A, B, and C conveniently located between the openings 5 and 6. It will be observed that since the openings 5 and 6 are only a short distance apart and upon the same side of the enclosure, a single operator standing at the 105 side of the enclosure between said openings may insert the articles to be washed through 110

the opening 5, manipulate the valves A, B, and C, and remove the finished or washed articles from the opening 6 without being compelled to travel materially in either direction along the enclosure.

Various devices may be adopted, if desired, to propel mechanically the articles through the tunnel. For example, a pusher 9 may be arranged over the open vat 4 at the inlet 10 end of the tunnel for engagement with the last article or case 8 inserted through the inlet opening 5, and this pusher may be power operated by utilizing a cylinder 10 into which the outer end of the pusher ex- 15 tends as a piston. A pipe 11 supplying a source of compressed fluid to the cylinder extends along the front of the tank or vat to a point between the openings 5 and 6, and there is provided with a self-venting 20 valve D having a manually operated control member 12, the pipe 11 then extending to a source of compressed fluid.

By pushing the control element 12 against the enclosure, the valve is opened and compressed fluid admitted to the cylinder 10 to operate the pusher 9 in a manner to propel the last inserted article or case 8 one step lengthwise along the tunnel towards the opening 6, such a propulsion being shown 25 partially completed in both figures of the drawing. The operator pushes the member 12 in a manner to keep the valve of the pipe 11 open until the propulsion is completed, and during such propulsion the cases 8 with- 30 in the tunnel will be propelled one step along by pushing upon one another. When 35 the propulsion has been completed, the operator releases the control element 12 and the pusher 9 is automatically retracted by a suitable spring or weight W to permit in- 40 sertion of another article or case 8 to be washed through the inlet 5, removes the article then at the outlet end of the tunnel, and repeats the operation.

In view of the fact that the washing de- 45 vices utilize sprays, it is desirable to keep the openings 5 and 6 as small as possible in order to prevent spattering of the spray liquids or fluids outside of the tunnel. When 50 the articles to be washed are milk bottles, the openings 5 and 6 will be made of a size to pass nicely the usual holding bottle crates 8, but provision is made for enlarging the inlet and outlet openings when the device is 55 to be used for the washing of cans or larger articles or objects. For example, the lateral wall section 13 immediately above the opening 5 may be removably secured in any suit- 60 able manner, such as shown in dash lines at the top of Fig. 1, so as to permit of the insertion of the milk cans which are taller than the crates, and similarly the section 14 of the lateral wall of the enclosure which is im- 65 mediately above the outlet opening 6 may also be made removable, or vertically ad-

justable such as by sliding it vertically, out of its operative position so that the opening 6 may be enlarged vertically to permit the passage therethrough of taller articles, such as milk cans. The sections 13 and 14 are 70 shown in dash lines in Fig. 1, removed from the apparatus.

It will be obvious that various changes in the details, which have been herein-described and illustrated in order to explain the nature 75 of the invention, may be made by those skilled in the art within the principle and scope of the invention as expressed in the appended claims.

Claims:—

1. In a washer for bottles, cans and other like articles, an enclosure having a tunnel provided with guides for conveying an article to be washed along the same, said tunnel having separate openings in one side thereof 85 near its ends forming an inlet and an outlet and spaced apart a distance enabling an operator to stand between them and reach either without extensive movement along the tunnel.

2. In a washer for bottles, cans and other like articles, an enclosure having a tunnel provided with guides for conveying an article to be washed along the same, said tunnel having separate openings in one side 95 thereof near its ends forming an inlet and an outlet and spaced apart a distance enabling an operator to stand between them and reach either without extensive movement along the tunnel, means operative at the inlet end of the tunnel for propelling along the tunnel the articles inserted through said inlet, and a control element for said means accessible to said operator while standing between said openings.

3. In a washer for bottles, cans and other like articles, an enclosure having a tunnel through which an article to be washed is conveyed, said tunnel having separate lateral openings on the same side thereof forming 110 an inlet and an outlet spaced apart a distance enabling an operator to stand between them and reach either opening without extensive movement in either direction, said tunnel having guides extending through said 115 openings and along said tunnel, whereby said articles may be inserted through said inlet and ejected from the outlet by the pushing of one by another, and means operable upon the last inserted article for pushing that 120 article and the previously inserted ones along said tunnel and through said outlet in succession.

4. In a washer for bottles, cans, and other like articles, a tank, an enclosure supported over one section of the tank and having guides for conveying therethrough over said tank the articles to be washed, said enclosure having lateral openings at its ends and at the same side of the tank, and also having 130

guides extending laterally of the enclosure through said openings, and means cooperating with said enclosure and tank for washing the articles while passing through said enclosure.

5. In a washer for bottles, cans and other like articles, an enclosure having a tunnel with lateral openings on the same side thereof and spaced apart a distance such that an operator standing between them can reach either one for the insertion and removal of articles to be washed, said tunnel having guides for conveying articles through said openings and along said tunnel, and a mechanical device for engaging the articles inserted through one of said openings and pushing the same a step along said tunnel, and retractable to engage the last inserted articles successively.
10. In a washer for bottles, cans and other like articles, an enclosure having a tunnel with lateral openings on the same side thereof and spaced apart a distance such that an operator standing between them can reach either one for the insertion and removal of articles to be washed, said tunnel having guides for conveying articles through said openings and along said tunnel, and a mechanical device for engaging the articles inserted
15. through one of said openings and pushing the same a step along said tunnel, and retractable to engage the last inserted articles successively, and a control element for said device accessible for operation by an operator standing between said openings.

20. 6. In a washer for bottles, cans and other like articles, an enclosure having a tunnel with lateral openings on the same side thereof and spaced apart a distance such that an operator standing between them can reach either one for the insertion and removal of articles to be washed, said tunnel having guides for conveying articles through said openings and along said tunnel, a mechanical device for engaging the articles inserted
25. through one of said openings and pushing the same a step along said tunnel, and retractable to engage the last inserted articles successively, and a control element for said device accessible for operation by an operator standing between said openings.

30. 7. In a washer for bottles, cans and other

like articles, an enclosure having a tunnel with inlet and outlet openings on the same side thereof and spaced apart a short distance, said enclosure having guides extending through said openings and along the tunnel for guiding articles through the tunnel between said openings, a power operated device adjacent one opening for engaging the last inserted article and pushing it one step along said tunnel to provide a space for another article, and a controlling element for said power device disposed between said openings for operation by an operator standing between said openings.

8. In a washer for bottles, cans and other like articles, an enclosure having a tunnel through which an article to be washed is conveyed, said tunnel having separate lateral openings on the same side thereof forming an inlet and an outlet spaced apart a distance enabling an operator to stand between them and reach either opening without extensive movement in either direction, said tunnel having guides extending through said openings and along said tunnel, whereby said articles may be inserted through said inlet and ejected from the outlet by the pushing of one by another, means operable upon the last inserted article for pushing that article and the previously inserted ones along said tunnel and through said outlet in succession, and a controlling element for said pushing means disposed between said openings for operation by an operator standing between said openings.
